US0D1056984S

(12) **United States Design Patent** (10) Patent No.: **US D1,056,984 S**
(45) Date of Patent: ** Jan. 7, 2025

(54) **CONTAMINATION-RESISTANT ROBOT
PROTECTIVE COVERING**

(71) Applicant: **CREATEC LTD**, Cockermouth (GB)

(72) Inventor: **William Newsom**, Cockermouth (GB)

(73) Assignee: **CREATEC LTD**, Cockermouth (GB)

(**) Term: **15 Years**

(21) Appl. No.: **35/519,809**

(22) Filed: **Nov. 17, 2023**

(80) **Hague Agreement Data**

Int. Filing Date: **Nov. 17, 2023**

Int. Reg. No.: **DM/234567**

Int. Reg. Date: **Nov. 17, 2023**

Int. Reg. Pub. Date: **Jan. 26, 2024**

(57) **CLAIM**

The ornamental design for a contamination-resistant robot protective covering as shown and described.

DESCRIPTION

1.1 : Perspective

1.2 : Front

1.3 : Back

1.4 : Left

1.5 : Right

1.6 : Top

1.7 : Bottom

Broken lines provide environmental information and are not claimed as a feature of the design; Fine diagonal triple parallel lines represent transparency, fine double parallel lines represent contours, they do not illustrate an ornamentation or decoration of the surface of the suit.
